[57] CLAIM

The ornamental design of a housing for an electrical connector, as shown and described.

DESCRIPTION

FIG. 1 is a front perspective view of a housing for an electrical connector showing our new design. The broken line showing of the end apertures throughout the drawing figures is included for the purpose of illustrating environmental elements only and forms no part of the claimed design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side elevational view being a mirror image;

FIG. 7 is a cross-sectional view thereof taken along line 7—7 of FIG. 2.
